ABSTRACT OF THE DISCLOSURE

A telescopic rod is mounted on a support positioned above the ascension pipes of a coke oven battery and is arranged to move longitudinally along the coke oven battery to clean the respective ascension pipes extending upwardly from the coke oven chambers. The telescopic rod has a cleaning tool secured to the end portion that is arranged to be positioned in the ascension pipe and rotated by means of drive apparatus connected to the telescopic rod. The rod includes a longitudinal passageway therethrough for conveying air to the cleaning tools positioned on the end of the telescopic rod. Suitable retracting means is provided to retract the telescopic rod from the ascension pipe in order that the cleaning apparatus may be moved to an adjacent ascension pipe.

BACKGROUND OF THE INVENTION

(1) Field of the Invention

This invention relates to apparatus for cleaning the ascension pipes of a coke oven and more particularly to mobile cleaning apparatus for automatically cleaning the ascension pipes of a coke oven.

(2) Description of the Prior Art

The ascension pipes and ascension pipe openings in the coke oven roof frequently become obstructed by carbonaceous or graphitic deposits therein. This is especially true with the ascension pipes on high coke ovens. It is believed the carbonaceous or graphitic deposits begin by flue dust from the coal or coke adhering to the walls of the ascension pipe. The flue dust thus forms the basic structure for the precipitation of the carbonaceous or graphitic material that thereafter becomes hard.

In the past, the ascension pipes were manually cleaned by means of elongated rods that were introduced through openings in the upper portion of the ascension pipe. The rods, by a scraping action, removed the graphitic or carbonaceous deposits from the ascension pipe side walls. This manner of manually cleaning the ascension pipes was laborious and time-consuming. Further, since the cleaning was performed manually, under ordinary circumstances the ascension pipes of a charged coke oven would not be cleaned until the oven was pushed.

There is a need for apparatus to quickly, automatically and efficiently clean the ascension pipes of coke ovens.

SUMMARY OF THE INVENTION

This invention is directed to apparatus for cleaning the ascension pipes of a coke oven battery and includes a support means mounted on the coke oven battery above the ascension pipes of the coke oven. The support means is movable longitudinally along the coke oven battery. A cleaning tool support member is rotatably mounted on the support means and has a cleaning tool secured thereto. Means are provided to insert the cleaning tool support member into the ascension pipe and rotate the cleaning

2

tool support member so that the cleaning tool removes carbonaceous or graphitic deposits from the inner surface of the ascension pipe.

The cleaning tool support member includes a telescopic rod that is rotatably supported from a frame member. The telescopic rod has a longitudinal air passageway therethrough which is connected to passageways in the cleaning tool. A blower is provided to deliver air under pressure through the passageway in the telescopic rod to the cleaning tool. The segments of the telescopic rod are connected to a flexible member which is wound around a winch so that a rod may be extended into the ascension pipe and retracted therefrom.

With the above arrangement, the apparatus is positioned in overlying relation with an ascension pipe and the telescopic rod is extended to position the cleaning tool within the ascension pipe. The telescopic rod is rotated to remove the carbonaceous or graphitic deposits from the inner surface of the ascension pipe.

Accordingly, the principal object of this invention is to provide mobile apparatus for automatically cleaning the ascension pipes in a coke oven battery.

Another object of this invention is to provide apparatus for cleaning the ascension pipes of a coke oven battery when the coke oven is either charged or pushed.

These and other objects of this invention will be more completely disclosed and described in the following specification, the accompanying drawing and the appended claims.

BRIEF DESCRIPTION OF THE DRAWING

The figure illustrates in side elevation the improved apparatus for cleaning the ascension pipes of a coke oven.

DESCRIPTION OF THE PREFERRED EMBODIMENTS

Referring to the drawing there is illustrated our improved apparatus generally designated by the numeral 10 positioned above the coke oven battery having a roof portion 12 and a vertical ascension pipe 14 extending upwardly through the roof 12 and connected to the opening 16 in the coke oven roof 12. The top of the ascension pipe has an elbow 18 which discharges the gaseous products into a collecting main 20 that extends longitudinally along the coke oven battery. The ascension pipe 14 has a top opening 22 with a lid 24 for closing the opening 22. The apparatus for cleaning the ascension pipe is introduced into the inner portion of ascension pipe 14 through the access opening 22.

The cleaning apparatus 10 includes a multi-sectioned telescopic rod 26 that has an upper section 28, intermediate sections 30 and 32 and a lower section 34. The sections 28-34 have decreasing outer diameters so that the respective sections can telescope within each other, i.e., the lower section 34 telescoping within the intermediate section 32 and the intermediate sections 32 and 30 sequentially telescoping into the upper section 28. The rod sections 28-34 are preferably tubular for the passage of air therethrough, as later disclosed, and for the hoist cable to retract the sections of the rod 26. The sections 28-34 may have a general rectangular configuration or have suitable splines and spline receiving, recessed portions so that the rotation of rod upper section 28 is transmitted through the sections 30 and 32 to the lower section 34.

A cleaning tool 36 is connected to the lower end of the rod 26 and has cylindrical segments 38 and 40 of different diameters. The conical configuration of the pipe opening 16 in the oven roof in a plane perpendicular to the plane illustrated in the drawing is taken into consideration. The rotation of the rod 26 rotates the cleaning tool 36 and removes the carbonaceous and graphite de-

posit on the inner cylindrical wall of ascension pipe 14 and further remove any graphitic deposits in the opening 16 in roof 12.

The cleaning apparatus includes a frame member 42 which is mounted with propelling wheels 44 and 46 thereon. The wheels 44 and 46 are suitably positioned on rails 48 and are propelled by a drive mechanism schematically illustrated as a gear 50 secured to the axle 52 for wheels 44 and 46. The rails 48 are mounted on a support frame 54 which is secured to the buck stays 56 of the coke oven battery and extended longitudinally along the coke oven battery. Thus the frame 42 for the cleaning apparatus is arranged to move longitudinally along the coke oven battery above the ascension pipe 14.

A drum member or winch 58 is suitably connected to the frame 42 and has a cable 60 schematically illustrated in the drawing extend downwardly preferably through the telescopic rod 26 and is secured to the lower end of the rod 26 adjacent the cleaning tool 36. A suitable source of current, such as a trolley 62, provides power for the drum 58. The rod upper portion 28 has a gear 64 nonrotatably secured thereto that meshes with a gear 66 rotatably mounted on the frame member 42 and suitably driven by an electric motor (not shown). A blower 68 is mounted on the frame 42 and is connected by a conduit 70 to an annular conduit 72 that is suitably connected to the internal passageway formed within the telescopic rod 26. Air flows downwardly through the passageway within tubular rod 26 and outwardly through the plurality of radial openings 74 in the tool portions 38 and 40. A collar 76 is secured to the rod intermediate portion 30 and seats on the ascension pipe opening 22 so that the opening can also be cleaned for the lid 24 while the internal portion of the ascension pipe is being cleaned by the cleaning tool 36. The cleaning apparatus 10 can be actuated by means of control switches 78 which are accessible from the platform 80 above the collecting main 20.

With this apparatus, the ascension pipes 14 are rapidly and automatically cleaned by first positioning the movable frame 42 in overlying relation with the ascension pipe 14. The lid 24 on the ascension pipe is opened to provide access to the inner portion of ascension pipe 14 through opening 22. The winch 58 is actuated to extend the telescopic rod 26 to the position illustrated in the drawing. During the extension of the rod 26, the rod is rotated by means of gears 64 and 66 and air is supplied to the cleaning tool 36 by blower 68. Simultaneously with the cleaning of the internal portion of the ascension pipe 14, the seat for the lid 24 in opening 22 is cleaned by means of collar 76. After the ascension pipe 14 has been cleaned and all of the graphitic and carbonaceous material removed therefrom, the winch 58 is actuated to retract the sections of rod 26 so that the rod is removed from the ascension pipe 14. Thereafter, the drive mechanism is actuated to move the cleaning apparatus 10 so that the rod 26 is in overlying relation with an ascension pipe for cleaning. The above described procedure is repeated during the subsequent operation.

With this arrangement, ascension pipes can be quickly and automatically cleaned of carbonaceous and graphitic deposits on the inner wall and more frequent cleaning can take place to remove minor deposits of flue dust before the hard graphitic deposits form on the inner walls of the ascension pipe. Further, with this arrangement and apparatus, it is now possible to clean the ascension pipes either on a pushed oven or on a charged oven.

According to the provisions of the patent statutes, we have explained the principle, preferred construction and mode of operation of our invention and have illustrated and described what we now consider to represent its best embodiments. However, we desire to have it understood that, within the scope of the appended claims, the invention may be practiced otherwise than as specifically illustrated and described.

We claim:

1. Apparatus for cleaning the ascension pipes of a coke oven battery comprising, support means mounted on the coke oven battery above the ascension pipes associated with the coke oven, said support means being movable longitudinally along said coke oven battery, a tubular telescopic rod member rotatably mounted on said support means, said telescopic rod member having a plurality of sections of decreasing outer dimensions so that said sections telescope within each other, means non-rotatably connecting said plurality of sections, a cleaning tool connected to the bottom section of said telescopic rod member, a cable member extending downwardly through a passageway in said tubular telescopic rod member and connected at one end to the lower end of the bottom section, said cable member other end connected to a winch member positioned above said tubular telescopic rod member, means to unwind said cable from said winch and extend said plurality of sections of said telescopic rod member within said ascension pipe, and means to rotate said tubular telescopic rod member so that said cleaning tool removes carbonaceous or graphitic deposits from the inner surface of said ascension pipe.
2. Apparatus for cleaning the ascension pipes of a coke oven battery as set forth in claim 1 which, said cleaning tool includes passageways therethrough connected to said passageway in said tubular telescopic rod member, means to supply a gas under pressure through said passageway in said tubular telescopic rod member to said cleaning tool passageways for flow of said gas under pressure out of said cleaning tool passageways into said ascension pipe.
3. Apparatus for cleaning the ascension pipes of a coke oven battery as set forth in claim 1 in which said support means includes, a frame member mounted on propelling wheels, said propelling wheels positioned on longitudinally extending rails on a support member, said support member positioning said frame above said ascension pipes.
4. Apparatus for cleaning the ascension pipes of a coke oven battery as set forth in claim 3 which includes, means to propel said frame member.
5. Apparatus for cleaning the ascension pipes of a coke oven battery as set forth in claim 1 which includes, gear means connecting said telescopic rod member to drive means positioned on said support means so that drive means on said support means rotates said gear means and rotates said telescopic rod member.
6. Apparatus for cleaning the ascension pipes of a coke oven battery as set forth in claim 1 in which said tubular telescopic rod member includes, a collar member secured thereto, said collar member arranged to seat in the opening and rotate with said tubular telescopic rod member to clean the opening for the lid.
